CLAIM

The ornamental design for a drawer with divider, as shown and described.

DESCRIPTION

FIG. 1 is a front perspective view of the design in the housing with the divider;
 FIG. 2 is a front perspective view of the design slide out of the housing with the single divider;
 FIG. 3 is a front view of the design in the housing with the divider;
 FIG. 4 is a back view of the design in the housing with the divider;
 FIG. 5 is a left side view of the design in the housing with the divider;
 FIG. 6 is a right side view of the design in the housing with the divider;
 FIG. 7 is a top view of the design in the housing with the divider; and,
 FIG. 8 is a bottom view of the design in the housing with the divider.
 The broken lines shown in the drawings are for illustrative purposes only and form no part of the claimed design.
